UNITED STATES PATENT OFFICE

JOHN P. DORAU, OF PORTAGE, WISCONSIN

FOLDING IRONING TABLE

Application filed March 31, 1930. Serial No. 440,372.

This invention relates to improvements in folding ironing tables.

It is one of the objects of the present invention to provide an ironing table which, when in use, will be supported very rigidly and firmly, but which may be easily and quickly collapsed to a compact position so as to occupy a minimum amount of storage space when not in use.

10 A further object of the invention is to provide a folding ironing table supported by a pair of connected legs and a third leg, all extending outwardly from intermediate portions of the table, and the third leg and pair 15 of legs diverging with respect to each other, the pair of legs being provided with folding means for locking the same in a spread position when unfolded.

20 A further object of the invention is to provide a folding, three legged ironing table in which the legs and brace members therefor are all operatively connected so that a movement of one of said members will tend to move the others of said members also.

25 A further object of the invention is to provide a folding ironing table in which the legs and brace members therefor may be releasably, securely locked in open, unfolded position.

30 A further object of the invention is to provide a folding ironing table which is of very simple construction, is easily manipulated, is strong and durable, and is well adapted for the purposes described.

35 With the above and other objects in view, the invention consists of the improved folding ironing table, and its parts and combinations as set forth in the claims, and all equivalents thereof.

40 In the accompanying drawings in which the same reference characters indicate the same parts in all of the views:

Fig. 1 is a side view of the ironing table in open or unfolded position;

45 Fig. 2 is an inverted plan view thereof;

Fig. 3 is an inverted plan view of the ironing table in folded or closed position;

Fig. 4 is a side view of a modified form of ironing table in open position with part broken away and in section; and

Fig. 5 is a side view of another modified form of ironing table in open position with part broken away and in section.

Referring now to the drawings and particularly to Figs. 1, 2 and 3 thereof, it will appear that the numeral 8 indicates the board or table portion of the folding ironing table, and the same may be of any suitable shape, but is preferably of rectangular form with a tapered end portion 8'.

An elongated U-bracket 9 is secured transversely to an under, intermediate portion of the board, and there is also secured to the under surface of the board, transversely thereof, and somewhat closer to one end, a short 65 U-bracket 10.

For the purpose of assisting in the support of the board 8 a leg member 11 is provided, composed of a pair of members 11' secured together at their lower or outer ends and diverging upwardly, the upper end portions of said members 11' being pivotally attached to opposite end portions of the bracket 10, as at 12.

The board is also supported by a pair of 75 somewhat longer legs 13 which are pivotally secured at their upper end portions to the board said beveled ends will bear flatly against the under surface of the board, providing a steady support and limiting the opening or unfolding movement of said legs. The upper portions of said pair of legs 13 are 85 connected by a pair of diagonally extended, crossed chains 14.

An inner lower face portion of each of the legs 13 pivotally carries a bracket 15, to the flanges of which are pivotally connected the 90

inner end portions of links 16 and 17 respectively. The overlapping end portions of the links 16 and 17 are pivotally connected together, as at 18, and the link 17 is formed with a side recess 19 to receive a projecting end lug 20 on the link 16 to limit the unfolding movement of said links with respect to each other.

A pivot rod 21 extends transversely between upper portions of the leg members 11' and one end portion of a board brace 22 is pivotally mounted on said rod 21 between the members 11'. The other end portion of said brace is somewhat flattened and tapered, as at 23, and is adapted to releasably engage in a shouldered recess 24 formed in the under surface of the board 8, to releasably lock the legs in open position.

The medial closed end portion of an elongated V-shaped wire or flexible brace member 25 is pivotally extended through an enlarged end portion 26 of the locking brace 22, while the free end portions of said brace member 25 are hooked through openings in intermediate portions of the links 16 and 17, as at 27.

When the table is folded, the parts are arranged as shown in Fig. 3 with all of the legs and pivotal braces extended in the same direction and against the under surface of the board. To open or unfold the table, the leg 11 is moved away from the board, and inasmuch as said leg is connected to an end of the locking brace 22, and the brace 22 is connected with the legs 13 through the V-brace 25 and the links 16 and 17, when the leg 11 is unfolded, the legs 13 will also be moved away from the board toward open position. During this movement the free end portion 23 of the brace 22 will be drawn along the under surface of the board toward the recess 24 and may be snapped thereto. The legs 13 are spread and are releasably secured in their spread or diverged open position by forcing the links 16 and 17 to extended position with respect to each other with the lug 20 lodged within the recess 19. In open position, all of the legs 11 and 13 are diverged with respect to one another and they are all rigidly connected together and are releasably locked in their unfolded spread positions, whereby a very firm and stable support for the board member is provided. The brace members and links hold the legs, when in unfolded positions, taut and under some degree of tension.

In Fig. 4 a modification of the invention is illustrated, and in this form the locking brace 22a, at its inner end portion is pivotally attached to a bracket 28 carried by the under surface of the board 8 toward the tapered end 8'. The inner end portion of the locking brace 22a is beveled as at 29 to bear flatly against the under surface of the board, when said brace 22a is moved away from the board,

and to limit the pivotal movement of said member 22a. The free end portion of the brace 22a is formed along its top edge with a recess 30 to receive therein the transverse rod 21 when the parts are in open position. This form of table is also provided with a V-shaped flexible brace member 25 having its closed end portion looped or bent about the rod 21, while the free end portions of said member 25 are bent through openings therefor in the links 15 and 16, as in the principal form, and indicated at 27. When this form of table is folded, all of the legs lie flatly against the under surface of the board and extend toward the tapered end 8'. The brace 22a, disengaged from the rod 21, also lies flatly, extending through the leg members 11' and below the rod 21. To unfold the table, when the leg 11 is swung outwardly, because of the connection by the member 25, the legs 13 are also unfolded, and then the free end portion of the brace 22a is moved outwardly of the board and the rod 21 is ultimately permitted to snap into the recess 30, and all of the parts are releasably secured in open position.

In the second modification of the invention illustrated in Fig. 5, the board brace 22a is eliminated and in lieu thereof an end brace 22b is employed. Said brace 22b is pivotally connected at one end to a bracket 28' depending from an end portion of the board 8 opposite the reduced end portion 8'. The free end portion of said brace 22b is adapted, when the table parts are in open position, to extend between the leg members 11', and the lower edge of the free end portion of said member 22b is formed with a recess 30' to receive the rod 21, whereby the table is releasably locked in open position.

From the foregoing description, it will be seen that the improved folding ironing table is of simple and novel construction, and is well adapted for the purposes described.

What I claim as my invention is:

1. An ironing table, comprising a board member, a pair of legs pivotally connected to the bottom portion thereof, a third leg also pivotally connected to the bottom portion of the board, a brace member extended between a bottom portion of the board and said third leg, said brace member being pivotally connected at one end to one of the elements between which it is extended and having its other end free in inoperative position but releasably engageable in operative position with the other of said elements, a pair of links connecting the outer end portions of said pair of legs and freely pivotally connected together, and a flexible brace member extended between the pair of legs and the third leg.

2. An ironing table, comprising a board member, a pair of legs pivotally connected to the bottom portion thereof, a third leg

also pivotally connected to the bottom portion of the board, a brace member extended between a bottom portion of the board and said third leg, said brace member being pivotally connected at one end to one of the elements between which it is extended and having its free end releasably engageable with the other of said elements, a pair of foldably connected links hingedly connected at opposite ends to lower end portions of said pair of legs, and a flexible, V-shaped brace member connected at its closed end with said third leg and having its other end portions connected to intermediate portions of said links.

15 In testimony whereof I affix my signature.
JOHN P. DORAU.
